[57] CLAIM

The ornamental design for a vending machine for beverages, as shown and described.

DESCRIPTION

FIG. 1 is a top front and left side perspective view of a vending machine for beverages, showing my new design;

FIG. 2 is a left side elevational view thereof; and

FIG. 3 is a right side elevational view thereof. The broken lines indicating surface detail in FIGS. 1-3 are shown for illustrative purposes only.

FIG.1

FIG. 3

FIG. 2
